UNITED STATES PATENT OFFICE.

JOSEPH NEMEC, OF CHICAGO, ILLINOIS, ASSIGNOR OF ONE-THIRD TO ALBERT L. BEARDSLEY AND ONE-THIRD TO CHARLES E. OLIVER, BOTH OF CHICAGO, ILLINOIS.

DOOR-HOLDER.

1,241,478.

Specification of Letters Patent. Patented Sept. 25, 1917.

Application filed February 18, 1915. Serial No. 8,053.

To all whom it may concern:

Be it known that I, JOSEPH NEMEC, a subject of the Emperor of Austria, residing at Chicago, in the county of Cook and State of Illinois, have invented certain new and useful Improvements in Door-Holders, of which the following is a specification.

This invention relates to improvements in door holders, and has for its object to provide a device of that nature which may be used in combination with a door closing mechanism.

It has been found desirable, especially in connection with railway car doors, to provide some means of maintaining the door in open or partially open position at certain times. These doors, for obvious reasons, are equipped with automatic closing means serving to normally return the same to closed position, and these devices will ordinarily prevent the maintaining of the doors in such open position. Devices have been provided for this purpose such as foot depressible checks, wedges, etc., but the same are not satisfactory for many reasons.

My invention consists in providing an improved form of door holder which is preferably arranged in combination with the door returning mechanism, and which is operable at the will of the operator to coact with the door closing mechanism to prevent automatic closing of the door until the holder is thrown out of operative position.

Still another object is to provide a device of this nature which, while in operative relation with respect to the door closing means, will permit opening of the door, although preventing the returning of the same to closed position.

Still another object is the provision of an additional holding member coacting with an element of the door closing device, the same being operative preferably only at full open position of the door to maintain the same in such position and capable of being thrown out of operation by forcible starting of the door from open position.

These and other objects will be more fully described and set forth in the following specifications and shown in the accompanying drawings, in which:

Figure 1 is a front elevation of a door showing my invention applied thereto;

Fig. 2 is a plan view of a portion of the door closing and holding mechanism;

Fig. 3 is a vertical section through a portion of the same taken along the line 3—3 of Fig. 2;

Fig. 4 is a perspective of the cap member;

Fig. 5 is a perspective of the pawl mechanism;

Fig. 6 is a plan view of the additional check or retaining member;

Fig. 7 is a vertical section through a portion of the same, a part thereof being shown in elevation; and

Fig. 8 is a transverse section along the line 8—8 of Fig. 2.

Like numerals refer to like elements throughout the drawings.

In the embodiment of my invention shown and described, I have utilized a well known form of door closing mechanism indicated generally by numeral 10, see Fig. 1, the same comprising, among other elements, a rotatable shaft 11 operatively connected to what is known as a check device intended to cushion the final closing movement of the door. Inasmuch as this does not form a portion of my invention, and is not directly concerned therein, I have not deemed it necessary to describe the same. The return member 10 comprises also a casing 12 having the base flange 13 arranged to be attached by screws or the like to a door 14, as shown in Fig. 1. A detachable cap 15 is provided and is mounted upon and attached to the top of casing 12, as shown in Fig. 3, for example, being provided with the cut-out portions 15^a arranged to engage suitable upstanding shoulders upon the casing 12. A ratchet member, generally indicated by numeral 16, is provided, the same being formed with an elongated hub or sleeve 16^a closely fitting around and attached to the shaft 11. This ratchet member 16 is provided with the peripherally located ratchet teeth 16^b formed on the wheel portion 16^c. The latter is provided with a circular recess 16^d on its underside and closely fits upon the circular flange 15^b of the cap 15, the latter being apertured at 15^e to permit passage therethrough of the hub 16^a and shaft 11, as shown in Fig. 3, for example.

This construction provides a bearing for the ratchet wheel 16, the latter being arranged to rotate upon and relative to the cap 15, as will be apparent. A coiled spring 18 is carried in the casing 12, as is well known, in connection with these devices, the same having one end attached to the casing 110

and the other end attached to the hub 16^a so that rotation from rest of the latter will tend to coil the spring 18 more closely, the latter thereby operating to resist such movement from rest position, as I term it, and also operating to normally return the mechanism to rest position. As is usual in connection with these devices, I provide a crank arm 19 apertured at one end and attached 10 thereto to the ratchet wheel 16 and shaft 11 by means of a nut 20 threaded on a reduced end of the shaft 11, see Figs. 2 and 3. This crank arm is pivotally attached at its other end to a rod 21, the latter being operatively 15 attached to a plate 22 attached to the door jamb, or the like. This mechanism is common to door closing devices, and it will be readily apparent that when the door 14 is moved from closed position the rod 21 and 20 crank 19 will operate to partially rotate the shaft 11 and ratchet wheel 16 against the action of the spring 18. When the door is released the spring will normally return the same to rest or closed position.

25 The cap 15 is provided with the outwardly extending oppositely arranged block portions 15^d, slotted and apertured as indicated by numeral 15^e, see Fig. 3. Slidably mounted in one of these apertures 15^e is a pawl 30 25 having teeth 25^a, see Fig. 5, at one end arranged for engagement with the teeth 16^b of ratchet wheel 16. Lugs 15^g project outwardly from the cap 15 and are apertured as shown in Fig. 4, for example. A link 26 35 is pivotally attached to one of these lugs, as shown in Fig. 2, and is also pivotally attached at its other end to a cross arm 27 which fits in a slot 25^b in the pawl 25 and is pivotally attached thereto intermediate 40 its extremities. At an end this arm 27 is pivotally attached to a head 28 carried by a rod 29. The latter passes through an aperture in flange 30^a of bracket 30 which is attached by screws or the like to the door 14. 45 A spring 31 is coiled around the rod 29 and extends between the head 28 and the flange 30^a, as is shown in Fig. 1. At its other end the rod 29 is provided with the enlarged slotted portion 29^a which fits over a pin 32 50 carried by bell crank 33 pivotally mounted on a pin 34 at its vertex, this latter being carried by a circular plate 34^a, see Fig. 1. To the other arm of the bell crank 33 is pivotally attached a second rod 35 which terminates at its lower extremity in a knob or manually engageable portion 36, being provided with a projecting stud or the like which fits in a slot 37^a in a plate 37 attached to the door. This slot is angularly arranged 55 at its lower portion, as shown in dotted lines in Fig. 1, so that the knob 36 and rod 35 may be moved thereinto and retained in its lowermost position, as shown in Fig. 1.

The wheel portion 16^c of the ratchet member 16 is provided with four or more thread-

ed holes 16^m and the crank 19 is provided with a pair of apertures arranged to align with a corresponding pair of apertures 16^m so that bolts 16° may be inserted in such apertures to assist in securing the crank 19 to the ratchet member 16, as shown in Fig. 2. In many cases in normal use, it will not be found desirable to leave the door in open position and consequently the mechanism will be arranged, as shown in Fig. 1. Assuming, however, that it is desired to retain the door in open or partially open position the same may be opened to the place desired and the knob 36 moved sidewise to allow it to slide to the upper end of slot 37^a, this movement being effected by spring 31. At the same time the teeth of pawl 25 will engage the teeth of ratchet 16 and relative rotation of the latter with respect to the casing 12 and cap 15 will be prevented and consequently the spring 18 will not be able to return the shaft 16 to rest position so that the door will be retained in its desired open position. To release the same it is only necessary to draw the knob 36 downwardly, whereupon, as will be obvious, the rods 35 and 29 and bell crank 33 will be operated to withdraw the ratchet 25 from engagement with the teeth 16^b of ratchet wheel 16, whereupon the spring 18 will effect the closing of the door. I have preferably arranged the teeth 25^a of the pawl and teeth 16^b of the ratchet so that the latter will slip by the former against the action of spring 31, when the door is opened, so that if knob 36 has been allowed to ride to the upper portion of slot 37^a, opening of the door will not be prevented; consequently, it will be obvious that opening movement of the door may be effected no matter in what position the knob 36 may be.

As an additional check or holding means to maintain the door in fully open position independently of the mechanism just described, I provide a detent 40 having the wedged face 40^a carried by the plunger portion 40^b, the latter being mounted in a sleeve 41 of a bracket 41, the latter being preferably embedded in the top of the door. A coiled spring 42 is located around the plunger 40^b and coacts with a shoulder 40^c thereof to resist depression of the head and wedge 40^a. The underside of the crank 19 is provided with a suitable slot or depression 19^a arranged to coact with the check 40 preferably when the door is in fully open position, at which time the crank 19 will lie on the upper edge of the door and the wedge 40^a will enter the slot 19^a serving to retain the door in fully open position. To release the same it is merely necessary to forcibly start the door, the spring 42 permitting this starting movement whereupon the returning mechanism will operate to close the door.

It will be obvious that my device is susceptible of many modifications and improve-

ments, and I do not wish to be restricted to the form shown or described beyond the scope of the appended claims.

What I claim is:

member being provided with a portion mounted in a slotted plate.

6. A rotatable shaft, a ratchet member carried thereby, means to resist movement from normal or rest position of said shaft and member, said means being adapted to normally return said shaft and members to rest position, a pawl member arranged to engage said ratchet member to prevent return thereof to normal position, means to move said pawl out of engagement with said ratchet, said means comprising a bell crank, a rod attached thereto, a second rod also attached thereto, and a manually engageable member carried by said last named rod, said member being provided with a portion mounted in a slotted plate, said plate being arranged to engage and hold said mechanism to prevent engagement of said pawl with said ratchet when desired. 80

7. In combination, a door closing member comprising a rotatable member and a casing, a movement resisting and returning member operatively inserted between said rotatable member and casing, an apertured bearing block carried by said casing, a rotatable ratchet carried by said rotatable member, and a pawl slidably mounted in said bearing block for engagement with said ratchet. 85

8. In combination, a door closing member 90 comprising a rotatable member and a casing, a movement resisting and returning member operatively inserted between said rotatable member and casing, an apertured bearing block carried by said casing, a rotatable 95 ratchet carried by said rotatable member, a pawl slidably mounted in said bearing block for engagement with said ratchet, and means controlled from a distance to move said pawl into or out of engagement with said ratchet. 100

9. In combination, a door closing member comprising a rotatable member and a casing, a movement resisting and returning member operatively inserted between said rotatable member and casing, an apertured bearing block carried by said casing, a rotatable ratchet carried by said rotatable member, a pawl slidably mounted in said bearing block for engagement with said ratchet, means to move said pawl into or out of engagement with said ratchet, and means to normally hold said pawl in engagement with said ratchet. 105 110

In testimony whereof, I have subscribed my name.

JOSEPH NEMEC.
